DESIGN FOR A TELEPHONE DESK STAND

Ernest S. McLarn, Manhasset, and Charles A. Duran, Brooklyn, N. Y., assignors to International Standard Electric Corporation, New York, N. Y., a corporation of Delaware

Application April 11, 1944, Serial No. 113,225

Term of patent 14 years

(Cl. D26—14)

To all whom it may concern:

Be it known that we, Ernest S. McLarn and Charles A. Duran, citizens of the United States, residing at Manhasset, in the county of Nassau and State of New York, and Brooklyn, in the county of Kings and State of New York, respectively, have invented a new, original, and ornamental Design for Telephone Desk Stand, of which the following is a specification, reference being had to the accompanying drawings, forming part thereof.

Figure 1 is a front elevational view of a tele-

phone desk stand showing the new design; Figure 2 is a plan view of the telephone desk stand;

Figure 3 is a side elevational view of the telephone desk stand; and

Figure 4 is a rear elevational view of the telephone desk stand.

We claim:

The ornamental design for a telephone desk stand, as shown.

ERNEST S. McLARN.
CHARLES A. DURAN.
